UNITED STATES PATENT OFFICE.

SHREWSBURY B. MILLER, OF FAIRMONT, WEST VIRGINIA.

PLAYING-CARDS.

1,289,511.

Specification of Letters Patent.

Patented Dec. 31, 1918.

Application filed January 4, 1916. Serial No. 70,153.

To all whom it may concern:

Be it known that I, SHREWSBURY B. MILLER, a citizen of the United States, residing at Fairmont, in the county of Marion and 5 State of West Virginia, have invented certain new and useful Improvements in Playing-Cards, of which the following is a specification, reference being had therein to the accompanying drawing.

10 This invention relates to an improvement in a card game known as house tennis, the object being to provide a card game that simulates the outdoor game of tennis by means of a special pack of cards which are 15 played according to the rules of lawn tennis, by which all of the possibilities, chances and science of the game of tennis can be realized by the participants in the card game through the imaginary stroke of the racket in the 20 actual game, whereby the stroke may be scored as won or lost and the game continued to the finish.

Another object of my invention is to provide a card game in which the pack of cards 25 employed, composed of a hundred cards divided into ten variations, each variation indicating the result of a stroke and how it may be played according to the rules of the game.

30 Another object of my invention is to provide a set of playing cards by the use of which, the game of lawn tennis can be taught, as in playing the same, each player makes an imaginary stroke with the racket 35 so as to serve or return a service ball, and can be played by two or four persons as singles or doubles in tennis.

Other and further objects and advantages of the invention will be hereinafter set forth 40 and the novel features thereof defined by the appended claims.

In the drawings—

Figures 1 to 10, indicate plan views of the various forms of cards used to complete the 45 pack of one hundred cards.

In carrying out my invention, I employ a pack of cards, one hundred in number, composed of ten cards designated with the words "Out of bounds"; ten cards designated with the words "Let ball"; ten cards 50 designated with the words "Netted ball"; four cards designated with the words "Foot fault"; four cards designated with the words "Struck by ball"; ten cards designated with the words "Placement shot"; 55 six cards designated with the words "Service ace"; six cards designated with the words "Killed at net"; twenty-five cards designated with the words "Ball served"; and fifteen cards designated with the words "Ball returned"; each card of the entire pack having the directions printed thereon relating to the play designated so as to instruct the player as to whether or not the point is won or lost. 60

In playing the game, with two or four persons, so as to simulate singles or doubles in tennis, and when playing singles, three cards are dealt to each player, which forms a hand, and the remainder of the pack is 70 placed, face down, to be drawn from alternately by the players after making a play, thus each hand constantly holds three cards, which is the same in playing doubles, and in making a stroke or playing a card, the 75 cards are played on a separate pile, face up, and should the cards in the drawing pack be exhausted by the players before the set is finished, the pack of discarded cards is 80 shuffled again and placed, face down, as before for a drawing pack, and the game continues until the six or more games are played so that the opponents have either won or lost the set.

The entire pack of cards is shuffled and 85 redealt for each new set, and the method of keeping the score is the same as in lawn tennis, and it is not thought necessary to set forth the rules of the game, although the usual rules covering lawn tennis can be followed and I wish to reserve the right to 90 incorporate in connection with this game, the rules so as to instruct the players.

In playing doubles, the partners are arranged on the same side of the table as in 95 the game of lawn tennis, the players or the partners are both on the same side of the net and the opponent, diagonally opposite the server must return the ball, but if impossible to play without the loss of the point, the 100 partner may play, but in playing doubles, the card designated "Ball served" is not valid for a return stroke by the opponent of the server. The service remains to the side during the entire game but alternates between the partners after each point of the 105 game is won or lost and when the game is completed, the opposite side or opponents

from the original server, starts the serving, the service alternating between the sides after each game is played.

The game is begun by the player having 5 the first serve, and to put the ball in play, a good or valid play must be made by playing a card designated "Ball served" or a card designated "Service ace," and in the former, the opponents must return the play 10 by playing a valid return card, or a winning card and in case they cannot play a valid card, the point is lost.

The player having the service, is given a chance to play two cards corresponding to 15 the service of two balls in the actual game of lawn tennis and assuming that the server has sent the ball over the net by playing the card designated "Ball served," the opponent, may do either one of the following 20 things: first, he may return the ball by the proper card; second, he may win the point by playing the proper card; or third, he may lose the point by having to play a card that neither returns the ball nor wins the point, 25 this depending upon the cards which he holds in his hand, so that it will be seen that the possibilities, chances and science of a real lawn tennis game are realized by the participants in the card game.

30 The science of the game is realized by the player discarding from his hand in making a play, the cards of the least value, the cards of the greater value to be retained by the player for a future play.

35 After the ball has been placed in imagination, in play, it is sent back and forth over the net by the players in making the plays until one or the other of the players participating in the game, has won or lost a point, 40 and this is continued until the game is either won or lost.

From the foregoing description, it will be seen that I have provided a pack of playing cards designated with the various plays of a 45 game of tennis, so that the participants arranged upon the opposite sides of a table, alternately play a card which either wins, returns, or loses the play; thereby making it possible that the game of lawn tennis can be 50 very closely simulated as the players can make rallies and a love game can be won, or a deuce game played.

In Fig. 1, I have shown a card constructed as will be actually used having a diagram of 55 a tennis court and a pair of crossed rackets at each end thereof with a central ball and it is, of course, understood that each of the cards will be constructed in this manner.

While I have shown and described a pack 60 of cards constructed in a particular manner, I do not wish to limit myself to the use of any design on the face of the cards composing the pack or to the duplicate printing at each end thereof of the printed matter designating the character of the play or the

printed matter designating the instructions to the player, as a pack of cards could be constructed with simply printed matter thereon designating the character of the play with the instructions, or a pack of cards 70 could be constructed simply having printed matter thereon designating the character of the play and the knowledge of the game by the player, would be sufficient to instruct him how to play the game, and I do not wish to 75 limit myself to the particular arrangement of the printed matter and the design employed on the face of the cards.

I claim:

1. A deck of cards for use in playing a 80 card game of lawn tennis, comprising a series of sets of cards, each card of each set being provided with matter designating the character of play and the result of said play.

2. A deck of cards for use in playing a card game of lawn tennis, composed of a plurality of sets, each card of each set having matter designating the different strokes of the players and the results of said strokes. 90

3. A deck of cards, for use in playing a card game of lawn tennis, composed of a plurality of suits and a plurality of like cards in each suit, one of said suits having matter thereon representing the different 95 strokes of the players, and another of said suits having matter thereon representing the return balls by the opponent.

4. A deck of cards for use in playing a card game of lawn tennis, composed of cards 100 having matter printed thereon indicating different strokes of the players and the result thereof, and how it may be played according to the rules of the game.

5. A deck of cards to be used in playing a card game of lawn tennis, composed of a plurality of cards, each card having a primary designation of a play in the game, and a secondary designation of how it may be played according to the rules of the game. 110

6. A deck of cards for use in playing a card game of lawn tennis, composed of ten sets of cards, each card of each set being provided with matter designating the character of the play and the result of the play 115 as a primary designation, and how it may be played according to the rules of the game as a secondary designation.

7. A card game, comprising a deck of cards divided into a number of sets of cards, 120 composed of a set of "out of bounds" cards, a set of "let ball" cards, a set of "netted ball" cards, a set of "foot fault" cards, a set of "struck by ball" cards, a set of "placement shot" cards, a set of "service ace" 125 cards, a set of "killed at net" cards, a set of "ball served" cards, and a set of "ball returned" cards.

8. A deck of cards for use in playing a card game of lawn tennis, including a plu- 130

rality of suits and a plurality of like cards in each suit, each card of each suit having matter indicating the result of the stroke and how it may be played according to the 5 rules of the game.

9. A card game, comprising a deck of one hundred cards divided into ten sets of cards, composed of a set of ten "out of bound" cards, a set of ten "let ball" cards, a set of 10 ten "netted ball" cards, a set of four "foot fault" cards, a set of four "struck by ball" cards, a set of ten "placement shot" cards,

a set of six "service ace" cards, a set of six "killed at net" cards, a set of twenty five "ball served" cards, and a set of "ball returned" cards, each card having the result of the play. 15

In testimony whereof I hereunto affix my signature in the presence of two witnesses.
